UNITED STATES PATENT OFFICE.

JOHN D. LOWE, OF INDIANAPOLIS, INDIANA, ASSIGNOR TO LA FAYETTE MOTORS COMPANY, OF INDIANAPOLIS, INDIANA, A CORPORATION.

ANTIRATTLE DEVICE FOR STEERING DEVICES.

1,417,674.

Specification of Letters Patent. Patented May 30, 1922.

Application filed August 12, 1921. Serial No. 491,821.

To all whom it may concern:

Be it known that I, JOHN D. LOWE, a subject of the King of Great Britain, and a resident of Indianapolis, county of Marion, and 5 State of Indiana, have invented certain new and useful Antirattle Devices for Steering Devices; and I do hereby declare that the following is a full, clear, and exact description thereof, reference being had to the accompanying drawings, in which like numerals refer to like parts.

This invention relates to a steering column and the actuating tubes contained therein for use in connection with the operation 15 and control of motor vehicles.

The main object of the invention is to provide means for preventing rattling and eliminating vibration between the tubes contained in the steering column, wherein there 20 are three thin metal tubes contained in the steering column for controlling the spark and throttle and supporting the segment arm. These tubes are mounted in telescopic relation, each very slightly spaced apart so 25 that vibration or jarring of the steering mechanism may cause them to rattle and become noisy. Such rattling is prevented by piercing the tubes to form a plurality of tangs having a slight spring, which are 30 adapted to bear against the adjacent tube or shaft for yieldingly spacing it from the surrounding tube.

The full nature of this invention will be understood from the accompanying drawings and the following description and 35 claims.

Fig. 1 is a central vertical section through a steering column showing the actuating tubes in position therein. Fig. 2 is an enlarged section through a portion of the tubes. 40 Fig. 3 is a section taken on the line 3—3 of Fig. 2. Fig. 4 is a side elevation of one of the tubes showing a tang pierced therein.

In the drawings there is shown a steering 45 column for motor vehicles having an outer casing tube 10 and an inner steering tube 11, said tube 11 being keyed to the steering wheel 12 through the spiders 13. The steering tube 11 is keyed to the worm 14 which 50 actuates the steering segment 15 enclosed within the housing 16 in the usual manner. Mounted within the steering tube 11 and adjacent thereto, there is a supporting tube 17 for the segment arm 18 which extends 55 through the steering tube 11 and is secured

at the bottom of the column 10 by the reduced portion 19.

Mounted within the supporting tube 17 there is a throttle controlling tube 20 secured to the throttle lever 21 at the upper end 60 thereof and to the throttle controlling pinion 22 at the lower end. Contained within the tube 20 and extending therethrough there is a spark controlling tube 23 which is secured at the upper end to the spark lever 24 and at 65 the lower end to the spark actuating pinion 25.

As shown in the drawings the tubes 17, 20 and 23 are slightly spaced apart, and maintained in spaced relation with respect to 70 each other by piercing the tubes to form tangs adapted to resiliently engage the adjacent tube. The tube 17 is provided with inwardly extending tangs 26 and outwardly extending tangs 27 which are punched from 75 the metal in the usual and well known manner. The tangs 26 extend inwardly and resiliently engage the outer surface of the tube 20, and the tangs 27 project outwardly and resiliently engage the inner surface of the 80 steering tube 23 for spacing the tube 17 therefrom. By means of the tangs 26, the tube 20 is spaced from the tube 17, and by means of the tangs 28 the tube 23 is spaced from the tube 20. It will, therefore, be seen 85 that each of the tubes contained in the steering column are resiliently spaced from each other and maintained in spaced relation under spring tension so that no vibration or rattling will be set up between them. 90 Wherein a rod may be employed in the center of the column in place of the tube 23, the same arrangement of engaging and spacing tangs may be employed inasmuch as no tangs are provided on the central tube and 95 would therefore not be necessary on the central rod. A central rod may therefore be employed in place of the central tube as an equivalent therefor.

The invention claimed is:

1. A steering column for vehicles having a plurality of telescoping tubes contained therein, and means positioned between the adjacent surfaces of said tubes for preventing the engagement thereof whereby there 105 will be no rattling or vibration set up therein.

2. A steering column for vehicles having a plurality of actuating tubes contained therein, and a plurality of resilient members 110

positioned between the adjacent surfaces of said tubes for preventing the engagement thereof, whereby there will be no rattling or vibration set up therein.

- 5 3. A steering column for vehicles having a plurality of actuating tubes contained therein, and a plurality of tangs formed in the walls thereof and projecting laterally

therefrom into resilient engagement with the wall of the adjacent tube for maintaining said tube in spaced relation, whereby there will be no rattling or vibration set up therein. 10

In witness whereof, I have hereunto affixed my signature.

JOHN D. LOWE.
